US00D920911S

(12) **United States Design Patent** (10) **Patent No.:** **US D920,911 S**
(45) **Date of Patent:** **** Jun. 1, 2021**

(54) **COIL COMPONENT**

(71) Applicant: **SUMIDA CORPORATION**, Tokyo (JP)

(72) Inventor: **Hitoshi Moriya**, Natori (JP)

(73) Assignee: **SUMIDA CORPORATION**

(**) Term: **15 Years**

(21) Appl. No.: **29/698,487**

(22) Filed: **Jul. 17, 2019**

(30) **Foreign Application Priority Data**

Jan. 23, 2019 (JP) 2019-001225

Jan. 23, 2019 (JP) 2019-001226

(57) **CLAIM**

The ornamental design for a coil component, as shown and described.

DESCRIPTION

FIG. 1 is a front elevation view of a coil component, showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front, left side perspective view thereof; and,

FIG. 8 bottom, front, left side perspective view thereof.

1 Claim, 8 Drawing Sheets
